LOUIS A. SWEM, OF SEATTLE, WASHINGTON.

SPARK ARRESTER.

Continuation of application Serial No. 584,827, filed August 28, 1922. This application filed November 1, 1923. Serial No. 672,176.

My invention relates to the art of spark arresters. While my invention will be described as applied to a locomotive engine or the like, nevertheless, its scope is not to be limited to any such specific use.

Spark arresters as heretofore designed, which have spark extinguishing chambers wherein the exhaust steam, i. e. chamber wherein the steam extinguished cools the sparks so that they are harmless, make no use of the "back pressure" to assist in keeping down the number of sparks and to save the fuel consumed. The consumption of fuel in a locomotive is well known to be attended with a great waste, the percentage of loss being determined to be as great as ninety percent. While absolutely essential in locomotives, the straight draft, reinforced by the exhausting steam from the engine cylinders, is responsible for carrying out a large percentage of the fuel, not only in the form of large "live" sparks, but also in the form of finely powdered carbon. Moreover, spark arresters of present practice design do not greatly reduce the evil effects of smoke, incident to the combustion of coal or oil. Respecting oil, a large portion of this fuel is lost in the form of unburnt carbon, and accumulations of this carbon in the form of compact chunks in a highly heated condition are emitted by oil-burning engines. Often such back pressure has no outlet provided and the extinguished particles of partially burned fuel, or carbon, are collected in a pocket and need to be periodically removed. Thus, this is not only unsatisfactory from a mechanical point of view, but introduces a labor cost for such removal. Also, obviously, such back pressure reacts disadvantageously to the force of the draft. Also, it is important in effecting a separation of the denser portions from the less dense portions of the smoke that the smoke and steam be discharged into the spark extinguishing chamber in a direction away from the smoke outlet, and preferably caused to strike for the most part the extinguishing chamber wall oppositely disposed to the outlet, so that the smoke and steam strike the top of the extinguishing chamber after glancing from said wall.

Providing a locomotive smoke stack with a spark arrester necessarily reduces, at least to some extent, the magnitude of the forced draft, and reduces the steaming capacity of

the engine. This result follows naturally from making the course of the discharging stream of steam and smoke circuitous, that is, by impeding its course. Therefore, it is of the utmost importance to provide a spark arrester of such a character that the back pressure may be utilized as far as possible in increasing the draft,—that is, minimizing as greatly as possible the evil effect due to the adding of the arrester. Also, it is likewise important that the escape of the smoke-steam stream after extinguishing the sparks be facilitated as much as possible which avoids building up back pressure. Supplying the inverted cone with a top as hereinafter set forth accomplishes this result. A primary object of my invention is to provide a spark arrester of such a character that much of the back pressure will be utilized to reinforce the forced draft, and of such a character as to facilitate the escape of the smoke-steam stream after extinguishing the sparks, thereby minimizing as greatly as possible the ill effects of adding the arrester from the point of view of reducing the force of the draft.

Spark arresters of common practice design do not provide for varying the size of the spark extinguishing chamber and this is important in an efficiently operating arrester for the reason that in burning hard coal the quantity of gases is so much greater than the chamber capacity should be reduced; and vice versa for soft coal, when the quantity of unburnt gases is smaller than in the case of hard coal. When wood is used as the fuel, the capacity of said chamber should be even greater than when soft coal is used.

In general, the object of my invention is to provide a spark arrester which will overcome these objections. More particularly, a primary object of my invention is to provide a spark arrester which will effect a large percentage of saving in the fuel consumed by recovering the fuel values from the smoke. Again, a primary object is to provide a spark arrester which will eliminate, for the most part, the injurious effects of the back pressure and utilize such pressure to return the extinguished sparks or carbon to the fire box wherein they may be used as fuel, and wherein their discharge in a fine dust-like or powder condition produces, as it were, a spontaneous combustion.

greatly augmenting the temperature of the fire box and improving the combustion therein. Another primary object of my invention is to provide a new device and method of reducing the smoke nuisance incident to the burning of coal, wood or oil as fuel. Another primary object of my invention is to provide a spark arrester in which the discharging current from the stack chamber and the return back pressure current are separated, the said discharging current being directed away from the smoke outlet or to a particular portion of the extinguishing chamber. Finally, a primary object of my invention is to provide a spark arrester in which the outlet opening into the extinguishing chamber bears a definite ratio to the size of the stack opening.

In general, I attain these objects, (a) by providing a partition between said exhaust current and the return current extending to a point which lies substantially in the vertical plane passing through the edge of the opening in the top of the arrester; (b) by providing for a rapid expansion of the steam so as to reduce it to a very "wet" condition, so that said chamber is caused to function very much as a washing compartment for the smoke; (c) by providing for the return of the extinguished particles of carbon to the fire box or ash pit; (d) by providing for the area of the opening in the top of the arrester having a definite ratio to the annular area of the extinguishing chamber; and (e) by providing an extinguishing chamber which may be varied in size.

The above mentioned general objects of my invention, together with others inherent in the same, are attained by the mechanism illustrated in the following drawings, the same being merely a preferred exemplary form of embodiment of my invention, throughout which drawings like reference numerals indicate like parts:

Figure 1 is a view of my invention applied to a steam locomotive; and

Fig. 2 is a view in vertical cross-section of a spark arrester embodying my invention.

The stack chamber 3 is provided with an inner inverted frustum of a cone structure 4 of suitable material with respect to which an inverted cone 5 is concentrically suspended to form the obliquely directed channel 6 for an outlet for the exhausting steam and smoke. Above the cone 5, cylinder 7 is disposed, depending from the top 8 of the cylinder 9, said top having the outlet opening 10. An outer inverted frustum of a cone 11 is secured on its upper edge to the bottom edge of the cylinder 9, thus forming the spark extinguishing chamber 12. Cylinder 13 in turn is suspended to the bottom of said frustum of a cone 11. To the lower portion of the wall of said cylinder, the

hopper shaped collectors 14 and 15, (one on each side of the stack chamber), are made secure. Connected to said collectors, pipes 16 and 17 respectively extend downwardly and backwardly on both sides of the engine 70 and unite in pipe 18 leading to the fire box 19. A cylinder 20 is adjustably mounted on rods 21 for the purpose of changing the size of the extinguishing chamber 12.

The mode of operation of my device is 75 as follows:

The inverted cone 5 and the inverted frustum of cone 4 provide a diverging channel 6, ("diverging" by reason of expansion of the outlet area), for the smoke and steam. 80 This diverging channel 6 leads to the extinguishing chamber 12 disposed thereabove, formed by the cylinders 7, 9 and 20. The smoke and exhausting steam, upon emerging from the smoke stack chamber 3, is expanded 85 into a ring form by channel 6, having a greater discharging area than the stack outlet. This divergence, obviously, reduces the force of the emerging current and permits 90 it to become wet steam. The current is discharged in a direction away from the outlet 23, (said outlet being the opening between the bottom of the cylinder 20 and the top of the cone 5), and is discharged against the side wall of chamber 12 oppositely disposed to said opening 23. The matter of the direction of such discharge is important and vital in determining the efficiency of the arrester. This is particularly true when the back pressure is utilized to return the unburnt fuel to the fire box, where the amount of back pressure can be readily controlled by the sliding adjustable cylinder 20, because, obviously, to increase the chamber 12 100 by lowering cylinder 20 tends to build up pressure in said chamber. Also, manifestly, to lessen the size of chamber 12 is to permit a more ready escape of smoke and gases, so that back pressure cannot be developed, or at least, will be very greatly reduced. The matter of back pressure is 105 of the utmost importance in determining the operability of an arrester. The prime requisite of a locomotive necessarily is its ability to develop steam; for practical operation, therefore, an arrester to be utilizable must not materially interfere with the ability of the locomotive to develop the necessary steam for its practicable and efficient operation.

In this connection, experience has taught that satisfactory results are obtained.—(that is, non-interference with the steaming capacity of the engine), when the area of the opening 10 and the annular area of the extinguishing chamber 12 stand in the relation or ratio of one to two (1:2), that is, the annular area of the extinguishing chamber should be twice as large as the outlet area 10. Respecting the term "annular area of the extinguishing chamber",—by 110

this is meant the area of a plane passing through said extinguishing chamber at right angles to the vertical axis of the arrester, and bounded by, or lying between 5 the side walls of the cylinders 9 and 20.

In further explanation of the ratio of the area of the opening 10 to the annular area of the extinguishing chamber, let it be noted that the volume of the blast of smoke should 10 strike against the side wall of the cylinder 9; thence, against the top of the extinguishing chamber; thence, against the wall of the cylinder 20; thence, under cylinder 20; thence, against the top 25 of the cone 5; and, 15 thence, out through the opening 10. The top 25 serves as a deflector for the current, and prevents objectionable interference with the capacity of the engine to develop steam. This steaming capacity is a most important 20 feature and fundamental, as above mentioned, to the success of any spark arrester. Any cinders reaching this top 25 are of relatively small proportions and are extinguished, so far as any fire in them is concerned. 25 They are readily thrown out by reason of the deflecting function of the said top, which facilitates the escape of the smoke-steam stream after extinguishing the sparks. The easy escape of the stream 30 avoids building up back pressure. This blast has a certain velocity as well as volume. The escape area of the opening 10 and the area of the stack opening should stand in the relation or ratio in the range 35 between one to five (1:5) and one to seven (1:7). I find excellent results are obtained when this ratio is about one to six (1:6). Clearly, the area of the stack opening determines the volume of gases which must be 40 handled by the spark arrester. As the area of the opening 10 is reduced in proportion to the annular area of the extinguishing chamber, there will not be provided a sufficient opening for the ready escape of the 45 smoke and steam, so that there will be developed an undue back pressure. Equally manifest, however, is the fact that as the area of the opening 10 is increased in proportion to the annular area of the extinguishing chamber, the escape of the gases is 50 facilitated. From the point of view of proper designing and manufacturing, the size of the arrester is of prime importance, that is, it should not be unnecessarily large, 55 and hence, we are interested in determining the smallest proportions of an arrester to handle a given quantity of smoke and steam, and thus it is that we find that the area of the opening 10 must bear the relation to the area of the stack opening which lies in the range between five to one (5:1) and seven to one (7:1), respectively. I also find, 60 as above noted, that the ratio of the annular area of the extinguishing chamber should be about two to one (2:1) as respects the

area of the opening 10. These are primary factors and enter most emphatically into the efficiency of the operation of the arrester, even to the point of its being practically operable. 70

The discharging smoke and steam from the channel 6 should impinge upon the side wall of the cylinder 9 at a point below the top of said chamber about one-third or one-half the height of said cylinder. Experience has taught that this is a fairly constant 75 rate for best results.

The topmost edge of the wall constituting the frustum of the cone 4 preferably should not extend beyond the vertical line 24, that 80 is, the line lying in the vertical plane passing through the edge of the opening 10, or through the wall of the cylinder 20. The reason for this will be manifest from the following: It will be understood that the 85 escape of the steam and smoke through the stack is intermittent in character. There is a blast of steam followed by a period of quiet, and then another blast of steam, as the exhausting steam from the cylinders is 90 intermittently allowed to escape to create the forced draft of the locomotive. When a rush of steam and smoke has occurred, the particles of unburnt fuel are first cast 95 against the side wall of the cylinder 9, then against the top of the extinguishing chamber 12, and then against the cylinder 20 constituting the inner vertical wall of the extinguishing chamber 12. By this time the 100 force of the draft is largely expended, and the now heavy particles of unburnt fuel,—there being added to their weight the dampness of the extinguishing steam,—are caused to fall downwardly and strike against the inside of the wall constituting the frustum 105 of the cone 11 as indicated by the arrows. It will be understood that some of the particles of unburnt fuel may not be forced against all of the three walls of the extinguishing chamber as above described, but 110 may fall upon wall 11 directly after impinging upon the wall 8, constituting the top of the extinguishing chamber 12. The arrows in full line indicate the general course of the smoke, and indicate the general 115 course of the blast, while the arrows in dotted line indicate the general course of the extinguished sparks. In this wise, it will be noted that the course of the extinguished 120 sparks is across the course of the blast, but it will be observed that said crossing is not simultaneous, but the crossing of the extinguished sparks of said course is subsequent in time, that is, during the period of relative quiet between the blasts. Having cone 125 4 wall stop at the vertical line 24 obviously provides for a larger number of the cinders passing direct to the cinder collectors.

Having set forth the factors which determine the back pressure, be it noted that 130

this back pressure should be sufficient to carry the extinguished sparks through the discharging outlets provided therefor, and preferably these should be carried to the fire box, for the second purpose and use of the back pressure is that it is utilized in my device to produce a forced draft to the fire, thereby providing for more complete combustion of the fuel, and diminishing the ill effects of reducing the force of the draft by providing the locomotive with the spark arrester. Thus, the back pressure of the arrester is utilized to keep the fire under a forced draft almost continuously. "Forced draft" as here used refers to the creating of a draft through the fire box, whether it be by the greater impulse of suction due to the escaping of the steam, or to the direct draft through the fire resulting from the escape of the back pressure through pipe 18.

Different engines of the same make and design and size for some reason have varied capacities of developing steam, so that it is essential to have means to vary the capacity of the extinguishing chamber. One form of such means may be the cylinder 20, which, as herein illustrated, may be raised or lowered to vary the capacity of said chamber.

Obviously, changes may be made in the form, dimensions, and arrangement of the parts of my invention, without departing from the principle thereof, the above setting forth only a preferred form of embodiment.

I claim:

1. An engine spark arrester embodying a smoke stack member; an inverted frustum of a cone mounted thereon; an inverted cone axially disposed within said frustum of a cone forming therewith a passageway; a second inverted frustum of a cone surrounding said first mentioned frustum of a cone, the diverging walls of said cone frustums and said cone starting from substantially the same plane as a base; a cylinder mounted on the top of said second frustum of a cone; a top for said cylinder; an axially disposed outlet opening in said top; a cylinder depending from the edges of said outlet opening spaced above said cone, forming an extinguishing chamber with said top and first mentioned cylinder, said passageway being disposed to direct the engine smoke-steam stream against the side wall of said extinguishing chamber previous to impingement against said top; and cinder collecting members having an open outlet, said members being operatively disposed with respect to said second frustum of a cone.

2. An engine spark arrester embodying a smoke stack member; an inverted frustum of a cone mounted thereon; an inverted cone axially disposed within said

frustum of a cone, forming therewith a passageway; a second inverted frustum of a cone surrounding said first mentioned frustum of a cone, the diverging walls of said cone frustums and said cone starting from substantially the same plane as a base; a cylinder mounted on the top of said second frustum of a cone; a top for said cylinder; an axially disposed outlet opening in said top; a cylinder depending from the edges of said outlet opening spaced above said cone, forming an extinguishing chamber with said top and first mentioned cylinder, said passageway being disposed to direct the engine smoke-steam stream against the side wall of said extinguishing chamber previous to impingement against said top; and cinder collecting members having an open outlet secured to the bottom of said third cylinder.

3. An engine spark arrester embodying a smoke stack member; an inverted frustum of a cone mounted thereon; an inverted cone axially disposed within said frustum of a cone forming therewith a passageway; a top for said cone whereby said top may operate as a deflector for the escaping smoke-steam stream; a second inverted frustum of a cone surrounding said first mentioned frustum of a cone; a cylinder mounted on the top of said second frustum of a cone; a top for said cylinder; an axially disposed outlet opening in said cylinder top; a cylinder depending from the edges of said outlet opening spaced above said cone, forming an extinguishing chamber with said cylinder top and first mentioned cylinder, said passageway being disposed to direct the engine smoke-steam stream against the side wall of said extinguishing chamber previous to impingement against said cylinder top; and cinder collecting members having an open outlet, said members being operatively disposed with respect to said second frustum of a cone.

4. An engine spark arrester embodying a smoke stack member; an inverted frustum of a cone mounted thereon; an inverted cone axially disposed within said frustum of a cone, forming therewith a passageway; a top for said cone whereby said top may operate as a deflector for the escaping smoke-steam stream; a second inverted frustum of a cone surrounding said first mentioned frustum of a cone; a cylinder mounted on the top of said second frustum of a cone; a top for said cylinder; an axially disposed outlet opening in said cylinder top; a cylinder depending from the edges of said outlet opening spaced above said cone, forming an extinguishing chamber with said cylinder top and first mentioned cylinder, said passageway being disposed to direct the en-

gine smoke-steam stream against the side wall of said extinguishing chamber previous to impingement against said cylinder top; a third cylinder depending from the bottom of said second frustum of a cone; and cinder collecting members having an open outlet secured to the bottom of said third cylinder.

5. An engine spark arrester embodying a smoke stack member; an inverted frustum of a cone mounted thereon; an inverted cone axially disposed within said frustum of a cone forming therewith a passageway; a second inverted frustum of a cone surrounding said first mentioned frustum of a cone; a cylinder mounted on the top of said second frustum of a cone; a top for said cylinder; an axially disposed outlet opening in said top; a cylinder depending from the edges of said outlet opening spaced above said cone, forming an extinguishing chamber with said top and first mentioned cylinder, the uppermost edge of said first mentioned frustum of a cone extending to a point substantially in a vertical line through the wall of said 25 depending cylinder; and cinder collecting members.

6. An engine spark arrester embodying a smoke stack member; an inverted frustum of a cone mounted thereon; an inverted cone axially disposed within said frustum of a cone forming therewith a passageway; a second inverted frustum of a cone surrounding said first mentioned frustum of a cone; a cylinder mounted on the top of said second frustum of a cone; a top for said cylinder; an axially disposed outlet opening in said top; a cylinder depending from the edges of said outlet opening spaced above said cone forming an extinguishing chamber with said top and first mentioned cylinder, said passageway being disposed to direct the engine smoke-steam stream against the side wall of said extinguishing chamber, the uppermost edge of said first mentioned frustum of a cone extending to a point substantially in a vertical line through the wall of said depending cylinder; and cinder collecting members, whereby extinguished cinders may fall during the interval between the engine exhaust periods across said passageway.

7. An engine spark arrester embodying a smoke stack member; an inverted frustum of a cone mounted thereon; an inverted cone axially disposed within said frustum of a cone forming therewith a passageway; a second frustum of a cone surrounding said first mentioned frustum of a cone; a cylinder mounted on the top of said second frustum of a cone; a top for said cylinder; an axially disposed outlet opening in said top, the area of said opening and the area of said smoke stack having a ratio, respectively, one to the other, which lies in the range of five to one (5:1) and seven to one (7:1); a cylinder de-

pending from the edges of said outlet opening spaced above said cone forming an extinguishing chamber with said top and first mentioned cylinder; and cinder collecting members.

8. An engine spark arrester embodying a smoke stack member; an inverted frustum of a cone mounted thereon; an inverted cone axially disposed within said frustum of a cone forming therewith a passageway; a second inverted frustum of a cone surrounding said first mentioned frustum of a cone; a cylinder mounted on the top of said second frustum of a cone; a top for said cylinder; an axially disposed outlet opening in said top; a cylinder depending from the edges of said outlet opening spaced above said cone, forming an extinguishing chamber with said top and first mentioned cylinder, the area of said outlet opening and the annular area of said extinguishing chamber having a ratio, respectively, which is substantially not less than one to two (1:2); and cinder collecting members.

9. An engine spark arrester embodying a smoke stack member; an inverted frustum of a cone mounted thereon; an inverted cone axially disposed within said frustum of a cone forming therewith a passageway; a second inverted frustum of a cone surrounding said first mentioned frustum of a cone; a cylinder mounted on the top of said second frustum of a cone; a top for said cylinder; an axially disposed outlet opening in said top, the area of said opening and the area of said smoke stack having a ratio, respectively, one to the other, which lies in the range of five to one (5:1) and seven to one (7:1); a cylinder depending from the edges of said outlet opening spaced above said cone, forming an extinguishing chamber with said top and first mentioned cylinder, the area of said outlet opening and the annular area of said extinguishing chamber having a ratio, respectively, which is substantially not less than one to two (1:2); and cinder collecting members.

10. An engine spark arrester embodying a smoke stack member; an inverted frustum of a cone mounted thereon; an inverted cone axially disposed within said frustum of a cone forming therewith a passageway; a second inverted frustum of a cone surrounding said first mentioned frustum of a cone; a cylinder mounted on the top of said second frustum of a cone; a top for said cylinder; an axially disposed outlet opening in said top; a vertically adjustable cylinder depending from the edges of said outlet opening, spaced above said cone, forming an extinguishing chamber with said top and first mentioned cylinder, the uppermost edge of said first mentioned frustum of a cone extending to a point substantially in a vertical line through the wall of said depend-

ing cylinder; and cinder collecting members.

11. An engine spark arrester embodying a smoke stack member; an inverted frustum of a cone mounted thereon; an inverted cone axially disposed within said frustum of a cone forming therewith a passageway; a second inverted frustum of a cone surrounding said first mentioned frustum of a cone; a cylinder mounted on the top of said second frustum of a cone; a top for said cylinder; an axially disposed outlet opening in said top; a cylinder depending from the edges of said outlet opening spaced above said cone, forming an extinguishing chamber with said top and first mentioned cylinder, said passageway being disposed to direct the engine smoke-steam stream

against the side wall of said extinguishing chamber, the uppermost edge of said first mentioned frustum of a cone extending to 20 a point substantially in a vertical line through the wall of said depending cylinder; a third cylinder depending from the bottom of said second frustum of a cone; and cinder collecting members having an 25 open outlet secured to the bottom of said third cylinder, whereby extinguished cinders may fall during the interval between the engine exhaust periods across said passageway.

In witness whereof, I hereunto subscribe my name this 27th day of October, A. D. 1923.

LOUIS A. SWEM.
